CLAIM

The ornamental design for an end cap for golf club grip, as shown and described.

DESCRIPTION

FIG. 1 is a perspective view of the end cap from the end attached to the grip;

FIG. 2 is a perspective view thereof from the outer end;

FIG. 3 is a top view thereof;

FIG. 4 is a right side view thereof;

FIG. 5 is a bottom view thereof;

FIG. 6 is a left side view thereof;

FIG. 7 is an outer end view thereof; and,

FIG. 8 is a view from the end opposite FIG. 7.

The broken lines shown on the drawing figures forms no part of the claimed design.
